X-RAY APRON AND GLOVE RACK

Eric Hughes, 23919 W. Malibu Road,
Malibu, Calif. 90265

Filed Mar. 14, 1967, Ser. No. 6,217

Term of patent 7 years

Int. Cl. D24—02

U.S. Cl. D33—3

FIG. 1

FIG. 2

FIG. 3

FIG. 4

FIG. 5

FIGURE 1 is a perspective view of an X-ray apron and glove rack showing my new design;

FIGURE 2 is a top plan view thereof;

FIGURE 3 is a bottom plan view thereof;

FIGURE 4 is a front elevational view thereof; and,

FIGURE 5 is a side elevational view thereof.

The dominant features of my design reside in those portions shown in full lines on the drawings.

I claim:

The ornamental design for an X-ray apron and glove rack, substantially as shown and described.
